DESIGN FOR AN AUTOMOBILE RADIO AERIAL

Anthony J. Gardella and Charles W. Buckingham,
Chicago, Ill.

Application December 21, 1938, Serial No. 81,918

Term of patent 7 years

To all whom it may concern:

Be it known that Anthony J. Gardella and Charles W. Buckingham, citizens of the United States, residing at Chicago, in the county of Cook and State of Illinois, have invented a new, original, and ornamental Design for an Automobile Radio Aerial, of which the following is a specification, reference being had to the accompanying drawing, forming part thereof.

Figure 1 is a side elevational view of an automobile radio aerial, showing our new design.

Fig. 2 is a top plan of the aerial shown in Fig. 1.
Fig. 3 is an enlarged side view of the middle part of our said aerial.

We claim:

The ornamental design for an automobile radio aerial, as shown.

ANTHONY J. GARDELLA.
CHARLES W. BUCKINGHAM.
